METHOD AND APPARATUS FOR DEFLECTING A BORE HOLE

Douglas Ragland, Houston, Tex., assignor to Standard Oil Development Company, a corporation of Delaware

Application June 22, 1936, Serial No. 86,506

10 Claims. (Cl. 255—1)

This invention relates to improvements in effecting the deflection of a bore hole, such as a drilling well.

The invention will be fully understood from the following description, taken in connection with the accompanying drawings, in which latter—

Fig. 1 is a vertical, sectional view through the earth, showing a bore hole with the apparatus for deflecting the bore hole disposed therein.

10 Fig. 2 is a detailed view of that portion of the hole containing deflection apparatus, and

Fig. 3 is a vertical, sectional view, showing the deflected hole formed by deflection apparatus.

Fig. 4 is a detail view of the end of the drill 15 stem showing a conventional bit and reamer.

Referring to the drawings, reference numeral 1 designates the surface of the earth and 2 designates the bore hole, the course of which is to be deflected. The hole is drilled with the use of 20 rotary tools, including rotary 3 and a drill stem 4 through a Kelly or drive joint 5, a travelling block 6, a crown block 7, and a drawworks 21. The hole 2 has been substantially extended by drilling to the designation 9.

25 It is frequently necessary, or desirable, to deflect the course of the bore hole in a predetermined or an undetermined direction. Also, it may be desirable to cause the drift or slope of the bore hole, drilling well, or rotary hole to be 30 changed, increased, decreased, or remain fixed, whether the result is or is not predetermined, in whole or in part. The apparatus for accomplishing these results comprises a section of drill stem 10 formed of flexible material, a portion of which 35 is curved at 11 to a sufficient degree such that the bore end 13 of the section is disposed on one side of the bore hole, while that portion 14 of the section above the curved portion 11 is on the opposite side of the bore hole, as clearly illustrated in the figures. The drill stem may be 40 made of the usual flexible material of which drill stems are constructed, or it may be tempered, if desired.

In the embodiment illustrated, the curved portion 11 of that section of drill stem is supplied 45 with a reamer 15 and the lower end of the section is provided with a bit 17.

50 In utilizing the device, the hole is drilled by usual procedure to a given depth, at which point it is to be deflected. Alternatively, a drilled hole can be plugged back. The drill tools are then removed from the hole and the curved section of drill stem 10 is affixed to the bottom of the string of drill pipe 4. The string of drill pipe 55 with the curved section 10 is inserted into the

bore hole until the bit 17 is near the bottom 9 of the bore hole, or the top of the plug. In this position the bore end 13 of the drill stem 10 is on one side of the hole, while that portion 14 of the stem 10 above the curve is on the opposite 5 side of the hole. The drill stem is then oriented by turning the string of drill pipe until the bit 17 is on a predetermined side of the hole. It is understood that the drill pipe is oriented as it is lowered into the hole so that the position of 10 the plane or planes containing the stem 10 is always known. The drill pipe 4 is now lowered by means of drawworks 21 until the bit 17 is in engagement with the bottom 9 of the bore hole, or the top of the plug, and sufficient weight of 15 drill pipe, or pressure, is applied to the section 10 to force the bit 17 against the bottom of the hole and cause the curved portion 11 to take the position shown in dotted lines, designated 20, and illustrated in Figs. 1 and 2. The drill stem is 20 then rotated, continuing application of pressure to cause the curved portion 11 to remain in the dotted line position, and the plane or planes containing the stem 10 to remain fixed, while deepening the hole. As a result, the bit 17 is forced 25 in a lateral direction as illustrated at 22, in Fig. 3.

It will be understood that the section of drill pipe 10 which effects the change of direction of the bore hole may be made from a piece, section or bit of pipe, tube, or a hollow body of metal 30 or alloy, kinked, bent or curved in one or more points and provided with bits, points, rotary shoes, cutting edges or edge, placed at one or both ends of the section, or along the length of the section. Alternatively, the bits, points, rotary 35 shoes, cutting edges or edge, may be left off entirely and some of the advantages of the invention will be retained.

While the invention has been described as applied to directing the course of a bore hole in a 40 predetermined direction, it will be understood that it can be used to direct the hole in an undetermined direction, that it can be used to correct the direction of a hole to its initial direction and in causing the drift or slope of a bore hole, 45 drilling well, or rotary hole, to increase, decrease, or remain fixed, whether the result is or is not predetermined in whole or in part, and some of the advantages of the invention will be retained.

While the invention has been described as an 50 apparatus comprised of a section of drill stem 10 formed of flexible material, a portion 11 of which is curved to a sufficient degree such that the bore end 13 of the section is disposed on one side of the bore hole, while that portion 14 of the 55

section above the curved portion 11 is on the opposite side of the bore hole, it will be understood that the apparatus may be comprised of a section of drill stem formed of flexible material, 5 a portion or all of which is curved, and some of the advantages of the invention will be retained.

Various changes and alternate arrangements may be made within the scope of the appended claims, in which it is my intention to claim all 10 novelty inherent in the art as broadly as the prior art permits.

I claim:

1. The method of deflecting a bore hole, which comprises disposing in the hole a drill stem of 15 lesser diameter than the hole and of flexible material, a portion of which is curved longitudinally, whereby the lower end of the drill stem is on one side of the hole when that portion of the stem above the curved portion is on the opposite side 20 of the hole, applying sufficient weight to the stem to force the lower end against the bottom of the hole and to flex the material of part of the curved portion so that it bears against the side of the hole, rotating the stem continuously, and continuing 25 the application of weight to retain the curved portion in its flexed position and to retain the stem in a fixed plane or planes, while drilling the hole, whereby the course is deflected.

2. The method of deflecting a bore hole by disposing in the hole a drill stem of lesser diameter than the hole and of flexible material, a portion of which is curved, whereby the lower end of the drill stem is on one side of the hole when that portion of the stem above the curved portion is 35 on the opposite side of the hole, orienting the stem in the hole whereby the lower end is on a given side of the hole, applying sufficient weight to the stem to force the lower end against the bottom of the hole and to flex the material of 40 part of the curved portion so that it bears against the side of the hole, rotating the stem continuously, and continuing the application of weight to retain the curved portion in its flexed position and to retain the stem in a fixed plane or planes, while drilling the hole, whereby the course is to 45 be deflected in a predetermined direction.

3. Apparatus for deflecting a bore hole which comprises a drill stem of lesser diameter than the hole and of flexible material, a portion of which 50 is curved, whereby the lower end of the drill stem is on one side of the bore hole when the portion of the stem above the curved portion is on the opposite side of the hole.

4. Apparatus for deflecting a bore hole, which 55 comprises a drill stem of lesser diameter than the hole and of flexible material a portion of which is curved, whereby the lower end of the drill stem is on one side of the bore hole when the portion of the stem above the curved portion is 60 on the opposite side of the hole, and cutting members carried by the curved portion.

5. Apparatus for deflecting a bore hole, which 65 comprises a drill stem of lesser diameter than the hole and of flexible material, a portion of which is curved, whereby the lower end of the drill stem is on one side of the bore hole when the portion of the stem above the curved portion is on the

opposite side of the hole, and cutting members carried by the drill stem within the length of the curved portion.

6. Apparatus for deflecting a bore hole, which comprises a drill stem of lesser diameter than the 5 hole and of flexible material, a portion of which is curved, whereby the lower end of the drill stem is on one side of the bore hole when the portion of the stem above the curved portion is on the opposite side of the hole, and cutting members carried in the body of the drill stem within the length of the curved portion and at the end of the curved portion.

7. The method of deflecting a bore hole, which comprises disposing in the hole a drill stem of 15 lesser diameter than the hole and of flexible material, a portion of which is curved, applying sufficient weight to the stem to force the lower end against the bottom of the hole and to flex the material of part of the curved portion so that it 20 bears against the side of the hole, rotating the stem continuously, and continuing the application of weight to retain the curved portion in its flexed position and to retain the stem in a fixed plane or planes while drilling the hole, whereby the 25 course is deflected.

8. The method of deflecting a bore hole, which comprises disposing in the hole a drill stem of lesser diameter than the hole and of flexible material, a portion of which is curved, applying 30 sufficient weight to the stem to force the lower end against the bottom of the hole and to flex the material of part of the curved portion so that it bears against the side of the hole, rotating the stem continuously, and continuing the applica- 35 tion of weight to retain the curved portion in its flexed position and to retain the stem in a fixed plane or planes, while drilling the hole, whereby the course is deflected in a predetermined direction. 40

9. The method of deflecting a bore hole, which comprises disposing in the hole a curved drill stem of flexible material and of lesser diameter than the hole, applying sufficient weight to the stem to force the lower end against the bottom of 45 the hole and to flex the material of part of the curved portion so that it bears against the side of the hole, rotating the stem continuously, and continuing the application of weight to retain the curved portion in its flexed position and to retain 50 the stem in a fixed plane or planes while drilling the hole, whereby the course is deflected.

10. The method of deflecting a bore hole, which comprises disposing in the hole a curved drill stem of flexible material and of lesser diameter 55 than the hole, applying sufficient weight to the stem to force the lower end against the bottom of the hole and to flex the material of part of the curved portion so that it bears against the side of the hole, rotating the stem continuously, 60 and continuing the application of weight to retain the curved portion in its flexed position and to retain the stem in a fixed plane or planes, while drilling the hole, whereby the course is to be deflected in a predetermined direction. 65

DOUGLAS RAGLAND.
